(57) **CLAIM**

The ornamental design for a LED temporary work light, as shown and described.

DESCRIPTION

FIG. 1 is a top, rear and left side perspective view of a LED temporary work light showing my new design;

FIG. 2 is a top, front and right side perspective view thereof;

FIG. 3 is a bottom perspective view thereof;

FIG. 4 is a bottom, rear and left side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof; and,

FIG. 11 is a rear elevational view showing the LED temporary work light.

The cords and buckles shown in FIG. 11 illustrate environmental structure and form no part of the claimed design.

The broken lines illustrate portions of the article in the drawings that form no part of the claimed design.
